COMBINATION TOOL

Joseph N. Amigone, Buffalo, N. Y.

Application April 28, 1951, Serial No. 15,012

Term of patent 14 years

(Cl. D44—29)

To all whom it may concern:

Be it known that I, Joseph N. Amigone, a citizen of the United States, have invented a new, original, and ornamental Design for a Combination Tool, of which the following is a specification, reference being had to the accompanying drawing, forming part thereof, and wherein:

Fig. 1 is a plan view of a combination tool, showing my new design;

Fig. 2 is a fragmentary, side elevational view taken along line II—II of Fig. 1; and

Fig. 3 is a fragmentary detail view taken along line III—III of Fig. 1.

This application is a continuation-in-part of my co-pending application Serial No. D. 149,261, filed October

23, 1948, on a design for a combination tool, and which resulted in Patent No. D. 163,785, granted July 3, 1951.

I claim:

The ornamental design for a combination tool, as shown.
